UNITED STATES PATENT OFFICE.

URBAN C. THIES, OF DAYTON, OHIO.

BUILDING CONSTRUCTION.

Application filed September 24, 1925. Serial No. 38,359.

This invention relates to building construction, and the primary object is the provision of a building for use as an airplane hangar which will be conveniently made so as to facilitate the storage of a number of airplanes, and provide for their easy access, removal and storage.

A further object is the provision of a novel lighting system by designing the roof truss so that it is composed of a central portion and two outwardly projecting cantilever sides, the truss covering being applied to the bottom of the central portion and to the tops of the side portions. A series of windows is provided to interconnect the covering of the central section with the coverings of the outer sections, these windows being inclined upwardly and outwardly from the covering of the central section. In this manner a building is provided which will be easily ventilated and which will provide maximum lighting effect from the sun. The location of the windows as a part of the roof permits the sunlight to be admitted and also causes the direction of the beams upon the parts of the aircraft where they are most desired, namely upon the engine and nose portion of the airplane.

A further object of the invention is the provision of sliding doors which close opposite sides of the building so that airplanes may be admitted along the entire length of the building without interference from structural parts of the building.

The building is supported for the most part by a series of vertical columns positioned within the outlines of the building so as to be out of the way of the airplanes when they are moved into place.

Further objects of my invention will be more fully set forth in the following description and in the drawings in which

Fig. 1 is a vertical section taken through the building, and

Fig. 2 is a plan view thereof.

Referring more particularly to the drawings, a series of columns 1 form a support for a roof truss designated generally 2, this roof truss being formed of a number of parallel trusses 3. Each truss 3 is composed of a central portion 4 and overhanging cantilever side portions 5 and 6. The side cantilever portions 5 and 6 project outwardly from the center section 4, and are of substantially the same vertical extent at the inner ends as the vertical height of the inner

section 4. The water proof covering 7 is applied to the top part of the truss 5 and 6. The water proof covering 8 is applied to the lower portion of the central section 4 of the truss as shown in Fig. 1. The space between the lower covering 8 at the center of the truss, and the upper coverings 7 is closed by a series of windows 9 which are inclined upwardly and outwardly from the covering 8 and within the confines of the roof truss. The windows 9 may be provided with means for opening them or for permitting their automatic opening in case of fire, and their location near the center of the building and for its entire length permits the illumination of the interior of the building in an efficient manner, while at the same time providing for a rain proof and weather proof covering.

The building is provided with a sliding door 10 which extends substantially the entire length of the building along the two opposite sides thereof as indicated in Fig. 1. Space is thus permitted for the placing of aircraft in position within the building without interference with any of the structural parts of the building. The airplanes may be placed with their empennages together as indicated between the columns and in this manner a large number of airplanes may be stored in comparatively small space and any one of them instantly removed without interfering with any other airplane. The light shining through the depressed monitor by reason of the location of the windows illuminates the engine portion and nose of the airplanes where the light is most needed.

I am aware that various modifications and changes may be made without departing from the scope of my invention and I do not intend to be limited to the exact construction which has been chosen for purposes of illustration.

I claim:

1. In a building, a roof truss having a center section and an outer section tapering in vertical thickness, a covering for the lower part of said center section, a covering for the upper part of said outer section, and a window interconnecting said coverings and inclined upwardly and outwardly from said center section.

2. In a building, a roof truss having a center section and an outer section of substantially the same vertical height, a cover-

ing for the lower part of said center section, a covering for the upper part of said outer section, and a window interconnecting said coverings and inclined upwardly and outwardly from said center section.

3. In a building, a roof truss having a center section and two outer sections, one on each side thereof, a covering for the lower part of said center section, a covering 10 for the upper part of each of said outer sections, and a series of windows interconnecting the covering of said center section and the covering of said two outer sections, said windows being inclined upwardly and 15 outwardly from said center section.

4. In a building, a roof truss having a center section and two outer sections, one on each side thereof, said center section being of substantially the same vertical height 20 throughout, and said outer sections tapering outwardly from said center section, a covering for the lower part of said center section, a covering for the upper part of each of said outer sections, and a series of windows inter- 25 connecting the covering of said center section and the covering of said two outer sections, said windows being inclined upwardly and outwardly from said center section.

5. In a building, a series of vertical sup- 30 ports, a roof truss supported thereby and having a cantilever portion extending outwardly from said supports, a covering for the upper part of said cantilever portion, a covering for the lower part of the roof truss 35 adjacent to said cantilever portion, and a series of windows between said two cover- ings.

6. In a building, a series of columns, a roof truss supported thereby, and having two opposite sides extending outwardly cantilever fashion from the central portion of said truss and from said columns, a covering for said truss and a sliding door extending substantially the entire length of both 40 said opposite sides.

7. In an airplane hangar, a series of columns, a roof truss supported thereby and having two opposite sides extending outwardly cantilever fashion from the central portion of said truss and from said columns, 45 said two opposite sides of said roof truss tapering outwardly from said central portion, a covering for the upper portion of the outer section of said truss, a covering for the lower part of the central portion, a series of windows connecting the central portion with each outer portion and inclined upwardly and outwardly from the covering of said central section, and a sliding door 50 extending the entire length of both said opposite sides.

8. In an airplane hangar, a double row of vertical columns, a roof supported by said columns and projecting out from each row to form opposite cantilever side portions, a 55 sliding door closing substantially an entire side of the hangar, a second sliding door closing substantially the entire opposite side of the hangar so that an airplane may be moved into place with its empennage between two columns without disturbing any other airplane in the hangar.

In testimony whereof I affix my signature.
URBAN C. THIES.
